Primary Examiner — Karen S Acker*Assistant Examiner* — Jerry Shuan-Hua Hsu(74) *Attorney, Agent, or Firm* — Clause Eight IPS; Michael Catania(57) **CLAIM**

The ornamental design for an antenna assembly, as shown and described.

DESCRIPTION

FIG. 1 is a top plan view of an antenna assembly

FIG. 2 is a side elevation view of the antenna assembly of FIG. 1

FIG. 3 is a bottom plan view of the antenna assembly of FIG. 1

FIG. 4 is an exploded view of the antenna assembly of FIG. 1

FIG. 5 is an isolated isometric view of a top antenna element of the antenna assembly of FIG. 1.

FIG. 6 is a top plan view thereof

FIG. 7 is a front elevation view thereof

FIG. 8 is a side elevation view thereof; and,

FIG. 9 is a bottom plan view of the bottom antenna element of the antenna assembly of FIG. 1.

The broken lines in the drawings depict the unclaimed base portion of the antenna assembly. The broken lines form no part of the claimed design.
